[57] CLAIM

The ornamental design for a money clip, as shown and described.

DESCRIPTION

FIG. 1 is a perspective view of a money clip showing my new design in an closed position;

FIG. 2 is a perspective view of the invention shown in FIG. 1, illustrating an open position;

FIG. 3 is a top plan view of the invention shown in FIG. 1; FIG. 4 is a left side elevational view of the invention shown in FIG. 1, with the right side elevational view being a mirror image thereof;

FIG. 5 is a bottom plan view of the invention shown in FIG. 1;

FIG. 6 is a front elevational view of the invention shown in FIG. 1;

FIG. 7 is a back elevational view of the invention shown in FIG. 1;

FIG. 8 is a perspective view of a money clip showing a second embodiment of my new design in an closed position;

FIG. 9 is a perspective view of the invention shown in FIG. 8; illustrating an open position;

FIG. 10 is a top plan view of the invention shown in FIG. 8; FIG. 11 is a left side elevational view of the invention shown in FIG. 8, with the right side elevational view being a mirror image thereof;

FIG. 12 is a bottom plan view of the invention shown in FIG. 8;

FIG. 13 is a front elevational view of the invention shown in FIG. 8; and,

FIG. 14 is a back elevational view of the invention shown in FIG. 8.
